COMBINED CLASP AND HOOK

George S. Nalle, Jr., Austin, Tex.

Application November 26, 1951, Serial No. 17,523

Term of patent 14 years

(Cl. D80—8)

To all whom it may concern:

Be it known that I, George S. Nalle, Jr., a citizen of the United States, residing at 1003 Rio Grande, Austin 1, Texas, have invented a new, original, and ornamental Design for a Combined Clasp and Hook, of which the following is a specification, reference being had to the accompanying drawing, forming part hereof.

Figure 1 is a front elevational view of a combined clasp and hook, showing my new design, and

Figure 2 is an end view of the structure shown in Figure 1.

The characteristic features of my design reside in the specific rib and circle ornamentation on the outside surface of the combined clasp and hook, and the configuration of the inner surfaces of the clip portion which are visible through the transparent material of which the combined clasp and hook are made.

I claim:

The ornamental design for a combined clasp and hook, as shown and described.

GEORGE S. NALLE, JR.
